UNITED STATES PATENT OFFICE.

WILLIAM H. KISSEL, OF OMAHA, NEBRASKA.

DESIGN FOR A SPROCKET-WHEEL.

42,629.

Specification for Design.

Patented June 18, 1912.

Application filed March 8, 1912. Serial No. 682,534. Term of patent 7 years.

To all whom it may concern:

Be it known that I, WILLIAM H. KISSEL, a citizen of the United States, residing at Omaha, in the county of Douglas and State of Nebraska, have invented a new, original, and ornamental Design for a Sprocket-Wheel, of which the following is a specification, reference being had to the accompanying drawing, forming a part thereof.

Figure 1 is an end view of a sprocket wheel, showing my new design. Fig. 2 is a plan view of the same.

I claim:

The ornamental design for a sprocket wheel, as shown.

In testimony whereof I have affixed my signature in presence of two witnesses.

WILLIAM H. KISSEL.

Witnesses:

HIRAM A. STURGES,
